Patented Feb. 29, 1916.

UNITED STATES PATENT OFFICE.

HIRAM H. TAYLOR, OF WORCESTER, MASSACHUSETTS.

PATTERN-DRAFTING DEVICE.

1,173,226.

Specification of Letters Patent.

Patented Feb. 29, 1916.

Application filed November 7, 1913. Serial No. 799,666.

To all whom it may concern:

Be it known that I, HIRAM H. TAYLOR, a citizen of the United States, residing at Worcester, in the county of Worcester and State of Massachusetts, have invented certain new and useful Improvements in Pattern-Drafting Devices, of which the following is a specification.

My invention relates to the drafting of patterns for wearing apparel, and has for its object the provision of improved simple and practical means by which the material for the garment may be accurately cut to conform to the different sizes and proportions as may be necessary.

A further object of this invention is to provide pattern charts particularly adapted to the use to which they are to be put and which shall facilitate the cutting of the garment material.

With these and other objects in view my invention consists in the peculiar construction of a series of pattern charts, consisting of rows of perforations and scales, each numbered to correspond with the measures taken for the different parts for which they are to be used, and fully disclosed in the following detailed description which is to be read in connection with the accompanying drawings and more particularly pointed out in the appended claims.

Referring to the drawings in which are shown six charts for coats or waists designated respectively as Figures 1, 2, 3, 4, 5 and 6, Fig. 1 is a plan view of the front chart; Fig. 2 is a similar view of the back chart; Figs. 3 and 4 are views of the opposite sides of the dart chart; Fig. 5 is a plan view of the sleeve chart; Fig. 6 represents a chart for drafting the lines of the neck and armscye and other curves.

Referring to the drawings more particularly by letter, A A designate rows of perforations, preferably four in number, set on arcs of elliptic curves. These perforations as shown in Fig. 1 are divergently disposed and determine the dimension of the front of the neck.

A', Fig. 2, designates a row of perforations set on an arc of an elliptic curve, the function of said row of perforations being to determine the width of the back and position of the back shoulder line at the neck. The curved edge A², Fig. 2, is used to shape the line for the back of the neck.

B represents a chart of irregular curved form shown in Fig. 6.

B' shows the outer edge which is employed to draft the top of the sleeve in a child's garment or in shaping the lines over the hip.

B² shows the inner edge and is employed to shape the lines of the front of the neck and armscye, and the two curves are used for drafting collars and cuffs for coats and dresses, and in shaping the different curves and scrolls in fancy coats, waistcoats and waist or dress trimmings, or for any place where irregular curves are required.

The dimension and shape of the shoulder position is obtained by means of rows of perforations C C, Fig. 1, said perforations being divided by graduated spaces and set on compound curves. These perforations C C are for the front, while at C', Fig. 2 is a single row of perforations used to determine the position of the back of the shoulder. The length and shape of the shoulder line is determined by the use of the graduated scales D, Fig. 1, for the front and D', Fig. 2, for the back. These scales are arranged on compound curves, and the back scale D', Fig. 2, is graduated longer than the front scale D, Fig. 1, so that the front portion of the shoulder may be stretched slightly in making, thereby to conform in length to the back, and thus secure in the finished garment a perfectly fitting shoulder.

E, F, G' and H, Fig. 1, and E' and H', Fig. 2, are rows of graduated perforations set on arcs of elliptic curves, said scales being numbered to correspond with the bust measure.

E, Fig. 1, and E', Fig. 2, denote rows of perforations for use in obtaining the dimension of the bust and the location of the point where the back and front join at the armscye.

The row of perforations F, Fig. 1, determines the position of the armscye with reference to the chest measure, while the row of perforations G, Fig. 1, locates the depth of the armscye, and in conjunction with the row of perforations G', Fig. 1, and the dart chart, Fig. 3, hereinafter to be described, determine the height and position of the top of the darts. The armscye is shaped by the use of the chart B shown in Fig. 6.

H, Fig. 1 and H', Fig. 2, represent rows of perforations employed to determine the

point where the back and front join near the waistline. By placing the perforations corresponding to the bust measure in rows E' and H' Fig. 2, over the dots on the pattern made through the corresponding numbers in rows E and H, Fig. 1, the outline of the pattern is drafted in one piece, and the lines of the different sections can be located to agree with the lines of the design to be copied.

I, Fig. 1, is a graduated scale, cut to a certain curve placed on the back edge of the front, and the graduated scale I', Fig. 2, is cut to the same curve on the forward edge 15 of the back. These two scales are on corresponding portions of elliptic curves to enable the position of the waistline to be accurately determined from a given point at the armscye. The figures on these scales 20 correspond with the under arm measure in inches, and the curved edges of the scales are such as to enable the proper shaping of the under arm lines, or, should a different under arm line be desired, the dart chart, 25 Figs. 3 and 4, hereinafter to be described, may be used. At J, Fig. 1, on the front edge of said chart is a graduated scale set on a portion of an elliptic curve, and numbered to correspond with the length of front 30 measure taken from the neck to the waistline. Said scale and edge are used to determine the length and shape of the front or joining line, making a perfect French line for the front of the garment. The length 35 also determines the position of the waistline in front. The front of the waistline is shaped by the compound curved edge K, Fig. 1.

L, Fig. 1, designates a double row of perforations used to determine the width between the front line and the first dart. In drafting garments with the "tailor back" proper curves for the form seam are obtained by the use of the curved edge shown 45 in M and I, Fig. 1, the portion M being on an arc of an elliptic curve. The curved edge, M', Fig. 2, is used to shape the line for the back of the armscye. The edge N, Fig. 2, is used to locate the center back 50 line, and is provided with a scale N, which determines the length of the back from the neck line at center of the back, said scale N being numbered to correspond with the length of back measure taken from the neck 55 to the waistline. The length also determines the position of the waistline, at the center of the back, which connects with the front portion of the waistline at a position indicated by the scale I, according to the 60 under arm measure as heretofore described, the line being drawn by edge carrying a scale O; Fig. 2. This scale of inches O is placed at right angles to the scale N, these scales permitting the use of the square 65 when required. In order to cut the gar-

ment to fit closely in the back at the waist line, the back chart, Fig. 2, has been made wide enough at scale O to allow a dart to be taken out between the back and form lines.

Figs. 3 and 4, Fig. 4, being the reverse 70 side of Fig. 3, illustrate the dart chart previously referred to. In the said charts are two rows of perforations, P and P', which are on small arcs of elliptic curves and numbered to correspond with the figures on the 75 rows of perforations G and G', Fig. 1, and are used in connection with the same to locate the proper position of the top of the darts in accordance with the bust measure. At Q and Q', Fig. 3, are double rows of 80 perforations, graduated and set on small arcs of elliptic curves, the function of which is to locate the position of the back lines of the first and second darts at the waist line, and in connection with the row of perforations R', hereinafter described, and L, Fig. 85 1; to take out the proper amount for the darts in front at the waistline, according to the difference between the bust and waist measures. The corresponding perforations 90 in each of the four rows of Q and Q', are connected by bars or guide lines, each line being numbered according to the different sizes of darts, thus making less danger of mistakes in drafting the pattern, the perforation nearest the waistline corresponding 95 with the size of the darts being used. At R, Fig. 3, is a perforation employed for locating the position of the turn in the compound curve of the front line of the second 100 dart, and at R', Fig. 3, is a row of four perforations connected by a line, arranged parallel with edge S², for locating the position 105 of the front line of the second dart at the waistline. The perforation nearest the 110 waistline is used in order to give the same distance between the two darts for any length of waist. The edge S of the dart chart is a compound curve, the different portions of which are employed in shaping 115 the lines of the darts and for drafting the proper shape of the curved lines over the hip below the waistline, and of the form seam when required for the French back. The reverse side of edge S, Fig. 4, carries a 120 graduated scale S', for locating the proper position of the dart chart to obtain the correct curve of the back line of the first dart. The dart chart further carries a scale of inches S², which may be employed as desired.

The sleeve chart is shown in Fig. 5. The different rows of perforations being on portions of elliptic curves, the figures opposite the perforations being equal to the number 125 of inches in the different measures taken. The rows of perforations U and U' are employed to locate the lines of the under side of the sleeves at the armscye. The rows U and U² locate the lines of the upper side of 130

the sleeve at the armscye, and the three rows together determine the size of the sleeve according to the top-arm measure taken at the armscye. The row U^3 is used 5 to determine the highest point in the curve at the top of the sleeve.

The double rows of perforations U^4 and U^5 are used to locate the lines of the under 10 side of the sleeve at the elbow, and the rows U^4 and U^6 are employed to locate the lines of the upper side of the sleeve at the elbow, and the three rows together determine 15 the size of the elbow according to the elbow measure. The rows of perforations U^{10} and U^8 are used to locate the lines of the under 20 side of the sleeve at the hand, and the rows U^7 and U^9 locate the lines of the upper side of the sleeve at the hand, and the four rows together determine the size of the 25 sleeve at the hand, according to the hand measure. The concaved curved edge of the sleeve chart is used for shaping the inside lines of the sleeve. The scale V and the figures thereon are used to determine the 30 length of the sleeve according to the in-arm measure, taken from the armscye to the bend of the arm opposite the elbow, and thence to the hand. The compound curved form of edge V' is used for shaping the lines of the 35 outside of the sleeve. The scale V' and the figures thereon are used to determine the length of the outside line of the sleeve according to the out-arm measure taken from the armscye to the elbow, and to the hand. 40 In drafting the outside lines of the sleeve above the elbow for a stout arm, the chart is inverted to curve the lines the opposite way, thereby giving more room for the muscles of the arm just below the armscye without 45 increasing the size of the sleeve at the armscye. The compound curved form of edge W is employed in connection with the perforation made through scale U^3 , to shape the lines of the top of the sleeve, and the edge W' is for drawing the line at the hand.

The rows of perforations X , X' and X'' , and the numbers thereon are employed to locate the lines of the sleeve at the armscye when the top-arm measure exceeds 17.

To give a better idea of using the invention the following measures are given: 1, size of neck, 14; 2, length of shoulder, 6; 3, height of shoulder, 2; 4, size of bust, 40; 5, size of waist, 28; 6, length of under-arm, 55 $8\frac{1}{2}$; 7, length of back, 15; 8, length of front, 15; 9, size of hips, 42; 10, size of top-arm, 16; 11, size of elbow, 12; 12, size of hand, $8\frac{1}{2}$; 13, length of out-arm, to elbow, $13\frac{1}{2}$; 14, length of out-arm, to hand, 24; 15, length 60 of in-arm, to elbow, $8\frac{1}{2}$; 16, length of in-arm, to hand, 18. Place the chart, Fig. 1, on a large piece of paper with edge J toward the operator and make a mark or dash at 14 of scale J . Dot the neck measure, 65 14, in the four rows of perforations A , A ,

the length of shoulder 6 in the row of perforations, height 2, in C , C . Use one-half the bust measure, and dot through perforation 20, in rows E , F , G , G' and H . Move the chart to the right on the paper until 70 edge D touches the dot for the neck made through the perforation nearest the left hand edge of the chart and the shoulder dot, and draw a line to the length of shoulder measure 6, by scale D . Now move the chart 75 toward the operator until edge I touches the dots made through rows of perforations E and H , and mark the length of under-arm $8\frac{1}{2}$, by scale I . Move the chart from the operator until edge J touches the neck dot 80 nearest the operator and the dash made at 14 by scale J , and draw a line for the front of the garment to the length of front measure 15, on scale J . Move the chart to the left until the corner touches the front line 85 at 15, and the edge K touches the length of under-arm $8\frac{1}{2}$, and draw the waistline between the two points. Dot one-half the bust measure 20 in the row of perforations L , and remove the chart. This gives the front 90 pattern.

For the back place the chart Fig. 2 on with the edge I' toward the operator, put one-half the bust measure 20 in rows of perforations E' and H' , over dots made at 20 95 through rows E and H , and dot the length of shoulder 6 in the row of perforations C' , the neck measure 14 in row A' , and draw a straight line along the edge N . Move the chart to the right until edge D' touches the 100 dots made through rows of perforations A' and C' , and draw a line to length of shoulder measure 6, on scale D' . Move the chart from the operator until edge M' touches the length of shoulder 6, and the dot made 105 through row of perforations E' , and draw a line between the two points, for the back line of the armscye. Move the chart away until the edge N touches the straight line, and the edge A^2 touches the dot made through row 110 of perforations A' , and draw a line between the two points for the back line of the neck. Mark the length of back 15, on the straight line. Move the chart to the left until the right angle corner touches the length of 115 back 15, and the edge O touches the length of under-arm $8\frac{1}{2}$, and continue the waistline between the two points. Measure $\frac{3}{4}$ of an inch from the straight line on the waistline, and draw a line from there to the point 120 where the line drawn by A^2 and the straight line intersect, for the back line of the garment, and remove the chart. Shape the lines for the front of the neck and armscye by the edge B^2 of chart Fig. 6. 125

For the size of the dart at the waist take the difference between one-half the bust and waist measures, or 6. Place the chart Fig. 3 on the front draft with the narrow end touching the front line, and straight edge S^2 130

touching dots made through rows of perforations G and G', and dot one-half the bust measure 20, in rows of perforations P and P', for the top of the darts. Turn the dart chart with edge S toward the operator, the point touching the dot made through row P, the edge touching the dot made through row L, and draw a line to the waist line, and dot the size of dart 6, in the perforation nearest 5 the waistline of rows Q. Reverse the chart and place the dash corresponding with the size of dart 6 in the scale S', Fig. 4 (Fig. 4 being the reverse side of Fig. 3) at the top of the dart, the edge S touching the dot made through row Q and draw a line to the 10 waistline. Place the chart with the point on the curved edge of the wide end touching the dot made through row P', the edge S² touching the back line of the first dart, and 15 dot in the perforation nearest the waistline of row R', in perforation R and in the size of dart 6 in the perforation nearest the waistline of rows Q'. Allow the point to remain at the dot and swing the other end 20 toward the operator until the edge touches the dot made through row G' and draw a line to the waistline. Then move the chart to the left until the point on the narrow end touches the dot made through R, and the 25 curved edge, the top of the dart, and draw a line between the two points. Turn the chart around and place the same point at the same dot, the curved edge toward the operator and touching the dot made through 30 row R', and continue the line to the waistline. 35

Draft the lines back of the first and second darts according to the style of garment, and for a tight garment take out a dart of $\frac{5}{8}$ 40 of an inch between the back and front lines, and of $1\frac{1}{4}$ inches under the arm at the waistline, and nothing at the armscye.

To draft the sleeve, place the chart Fig. 5 45 with the curved end W to the left hand and edge V toward the operator, and dot the top-arm measure 16 in rows of perforations U, U', U², the elbow measure 12 in rows U⁴, U⁵, U⁶, the hand measure 8 $\frac{1}{2}$ in rows U⁷, U⁸, U¹⁰, and U⁹. Move the chart toward the 50 operator until 12 $\frac{1}{2}$ in the scale V' touches the dot made through row of perforations U⁶, and the edge touches the dot made through row U², and draw a line from the left hand end of the scale. Swing the opposite end 55 until it touches the dot made through row U⁹, and continue the line for the outside of the upper side of the sleeve. In the same manner draw a line past the dots made through rows of perforations U', U⁵, and U⁸, for the outside of the under side of the sleeve. 60

Draw the line for the inside of the upper and underside of the sleeve above the elbow in the same manner, by placing 8 $\frac{1}{2}$ in scale V at the dot made through row of perfora- 65

tions U⁴, the edge touching the dot made through the row U, and continue the line to the dot made through row U⁷ for the upper side of the sleeve below the elbow. Swing the chart from the operator until it touches the dots made through rows U⁴ and U¹⁰ and draw a line for the underside of the sleeve below the elbow. 70

Measure the length of the outside of the sleeve by placing the out-arm to elbow 75 measure 13 $\frac{1}{2}$ in scale V' at the elbow dot, and mark at the left hand end of the scale, and at the out-arm to hand measure 24. In the same manner, measure the length of the inside of the sleeve, using the in-arm to elbow measure 8 $\frac{1}{2}$, and the in-arm to hand measure 18, and measure by scale V. Locate the highest point of the top of the sleeve by placing the perforation corresponding with the top-arm measure in row 80 U², at the left hand end of the outside line of the upper side of the sleeve, let edge V' touch the line below the elbow and dot the top-arm measure 16 in row U³. Draw the line for the top of the upperside of the 85 sleeve by the curved edge W. Invert the chart and draw the top line of the under side of the sleeve by the same edge. Draft the line at the hand by edge W'. 90

To draft a sleeve when the top-arm measure exceeds 17. Dot through the perforations the same as for the regular sleeve using 17 instead of the top-arm measure in rows U, U' and U². Turn the chart with the curved end toward the operator and 100 place the perforations 17 in the rows X, X' and X², over the dots made through 17 in rows U, U' and U², and dot the top-arm measure, for example 22, in rows X, X' and 105 X² and draw the lines above the elbow to these dots, and finish the top of the sleeve the same as in size 17, finish below the elbow the same as the regular sleeve.

This invention is an improvement over my prior Patent No. 594,443, November 30, 110 1897, pattern drafting device, and is designed to facilitate the operation of the said chart.

The invention involves the same rules that govern in the geometrical method for obtaining the compound curves by the intersection of tangent lines, and the different portions of elliptic curves by the intersection of graduated lines at right angles, and also involves the principles that govern the 115 use of the steel square.

I claim as my invention:

1. The drafting device for apparel patterns having the diverging rows of perforations, A A at the neck, the rows of perforations lying on compound curves, C C at the shoulder, the graduated scale, D at the shoulder on a compound curve, the rows of perforations lying on portions of elliptic curves, E, F, G, G', and H for drafting the 120 125 130

bust and armscye, for locating the joining-point under the arm and in connection with the dart chart for locating the tops of the darts, the graduated scales set on portions 5 of elliptic curves, I and J, a compound curved edge, K for shaping the waistline, the double row of perforations L, and the curved edge, M all substantially as indicated.

10 2. The drafting device for apparel patterns having the row of perforations, A' and the curved edge A² for the back of the neck, the row of perforations set on a compound curve, C', the graduated scale also set on a compound curve, D' for the back shoulder, the rows of perforations lying on portions 15 of elliptic curves, E' and H', the graduated scale, I', said rows of perforations E' and H' curving upward toward the top of the chart from said scale I', the curved edge, M', the scales of inches, N and O, all substantially as and for the purpose set forth.

20 3. The drafting device for the darts having rows of perforations P, P', Q and Q', said row of perforations P arranged out of alinement with and below said row of perforations P', said row P passing diagonally through said rows of perforations Q, the rows of perforations Q' arranged parallel

above said rows Q, the single perforation R, 30 the further row of perforations R' arranged parallel to said rows Q', and also parallel to the scale edge S², the curved edge S, the scale thereon S' and the scale of inches S², all substantially as specified. 35

4. The drafting device for sleeve patterns having the series of rows of perforations U, U', U² and U³ at one end converging toward the elbow, the series of double rows of perforations U⁴, U⁵ and U⁶ across the same 40 at the elbow, the series of rows of perforations U⁷, U¹⁰, U⁸ and U⁹ at the opposite end also converging toward the elbow, the series of rows of perforations X, X' and X², two above running nearly parallel with and one 45 below running obliquely to the rows at the elbow and converging toward the outside edge of the sleeve chart, the scales V and V' arranged on compound curved edges, the curved edge W at the top and the straight 50 edge W' at the bottom all substantially as set forth.

In testimony whereof I affix my signature in presence of two witnesses.

HIRAM H. TAYLOR.
